UNITED STATES PATENT OFFICE.

CHARLES HENRY SMITH, OF PARK CITY, MONTANA.

DESIGN FOR A CORN-CUTTER.

SPECIFICATION forming part of Design No. 28,810, dated June 7, 1898.

Application filed April 12, 1898. Serial No. 677,374. Term of patent 14 years.

To all whom it may concern:

Be it known that I, CHARLES HENRY SMITH, a citizen of the United States, residing at Park City, in the county of Yellowstone and State 5 of Montana, have invented and produced a new and original Design for Corn-Cutters, of which the following is a specification, reference being had to the accompanying drawings, which form a part thereof, and in which—

- o Figure 1 is a side view of a corn-cutter, showing my new design; and Fig. 2 is an end view of the same.

The leading or material feature of my design consists of a flat portion a , of approximately semicircular outline, having segmental or rounded top edges a' , a straight bottom edge a^2 , and rounded or curved lower corners a^3 . The outer face of the member a at its bottom portion is beveled or inclined transversely, as at a^4 , said bevel extending downwardly to the straight bottom edge a^2 . The top portion of the member a is curved rearwardly in a straight or direct line, as at b , and from said rearward extension projects 15 a longitudinal cylindrical member c , which

has a globular or spherical enlargement c' at its rear end. The flat portion a is at an acute angle with relation to the longitudinal members c . The flat portion a is of an approximately semicircular outline, having no 30 straight sides except its bottom edge. In contour the segmental or rounded top edge a' extends in a continuous curved line from the top portion b downwardly to the bottom edge a^2 , the lower corner of said continuous 35 curve being turned inwardly to form the curved lower corner a^3 .

Having described my invention, I claim as new and desire to secure by Letters Patent—

The design for a corn-cutter, substantially 40 as herein shown and described.

In testimony that I claim the foregoing as my invention I have signed my name, in presence of the subscribing witnesses, this 1st day of April, 1898.

CHARLES HENRY SMITH.
